No. 792,200.

PATENTED JUNE 13, 1905.

VAN WYCK A. CROSHIER.

TIME STOCK FEEDER.

APPLICATION FILED JAN. 26, 1904.

2 SHEETS—SHEET 2.

UNITED STATES PATENT OFFICE.

VAN WYCK A. CROSHIER, OF FROSTBURG, MARYLAND.

TIME STOCK-FEEDER.

SPECIFICATION forming part of Letters Patent No. 792,200, dated June 13, 1905.

Application filed January 25, 1904. Serial No. 190,493.

To all whom it may concern:

Be it known that I, VAN WYCK A. CROSHIER, a citizen of the United States, residing at Frostburg, in the county of Allegany and State of Maryland, have invented a new and useful Automatic Stock-Feeder, of which the following is a specification.

This invention relates to a hopper adapted to be secured above a manger and to contain grain to be fed into the manger at a predetermined time and to be fed gradually as it is eaten by the stock.

The objects of my invention are to provide means for opening the lower end of the hopper automatically; and a further object is to provide means for regulating the rate of feed from the hopper after it has been opened.

My invention consists of the novel features of construction and combination of parts hereinafter described, particularly pointed out in the claims, and shown in the accompanying drawings, in which—

Figure 1 is a perspective view of my device placed in position. Fig. 2 is a vertical sectional view through the hoppers. Fig. 3 is a section on the line 3 3 of Fig. 2. Fig. 4 is a section on the line 4 4 of Fig. 2. Fig. 5 is a detail front view of the lower portion of the hopper, showing the adjustable sleeve for regulating the rate of the flow of grain. Fig. 6 is an outline elevation of the means for controlling the opening of the hoppers, and Fig. 7 is a perspective view of the bracket shown in elevation in Fig. 6.

In the drawings, A represents a suitable manger, and secured to the wall back of said manger is a hopper B, semiconical in shape and discharging at its lower end into a second hopper B', which incloses the lower apex portion of the hopper B. The rear flat wall of the hopper B is stamped or pressed inward along the longitudinal axis of the said wall, whereby a semicylindrical groove B² is formed. Extending through and adapted to rotate in this groove is a rod C, the rod extending a suitable distance above the hopper B, where it is bent at a right angle, as shown at C'. At its lower end the rod C rests on a bracket C³ and is angled, as shown at C², this angled portion being cut away along its upper face. On

this reduced or flattened portion of the part C² is secured a slide C⁴, adapted to close the lower end of the hopper B when the rod C is in one position and to swing from under the lower end of the hopper when the rod C is rotated in either direction. 55

At the lower end of the hopper B' is arranged a discharge-chute B³, which extends into the manger A, and on the chute B³ is arranged an adjustable sleeve D, the said sleeve 60 sliding on the discharge-chute B³ and being clamped in its adjusted position by a setscrew of the usual construction. At its lower end the sleeve D is diagonally cut away on the front side, as shown at D', and a curved 65 grain-guard is carried by this end of the shield, the guard D² extending on opposite sides of the sleeve. Through the bent portion C' of the rod C extends a rod E, arranged horizontally above the hopper and manger. 70 Connected to the ends of the rod E are chains E' and F, respectively, and these chains pass over idle pulleys G, arranged in alinement with and at opposite ends of the rod E. To the end of the chain E' is connected a weight E². 75

Arranged adjacent one end of the manger opposite the end adjacent the weight E² is a bracket H, cut out at H' to receive an alarm-clock of any desired make and having a stop-block H² arranged substantially in the plane 80 of the clock J². A rod J is connected by a link to the winding-stem J' of the clock, and this rod is adapted to be passed through a link of the chain F and to have its outer end extend under the stop-block when the winding-stem is in a vertical position, as shown in Fig. 6.

The operation of my device is as follows: The rod C is turned so that the slide C⁴ closes the lower end of the hopper B. The clock is 90 wound, and the alarm set to go off at the time it is desired to feed. The rod J is passed through a link in the chain F and caught under the block H². The weight E² is thereby held up. The hopper B is filled with grain 95 and the sleeve D adjusted the proper distance above the bottom of the manger to give the rate of feed desired. When the alarm goes off, the outer end of the rod J will be withdrawn by the rotation of the winding-stem J' 100

from contact with the block H^2 , and the weight will cause a partial rotation of the rod C , throwing the slide C^1 to one side and admitting the grain to the hopper B' , from which it will 5 pass through the discharge-chute and sleeve into the manger. By proper regulation of the sleeve D the rate of feed will be such that the grain will not feed faster than the stock can eat and properly masticate it. When the hopper B is low, a large-mesh screen K may be 10 placed over the hopper to prevent the stock from getting at the feed while in that hopper.

It is obvious that as many mangers as may be desired can be equipped with the hoppers 15 and that all of them may be controlled by one weight and from one common alarm. It will also be obvious that as the rod C will rotate in either direction and the slide C^1 swing in either direction it is immaterial which side of 20 the stall the weight and the clock are placed on, and the weight and clock may be reversed without affecting the operation of the device. It is also obvious that the rod J may be released by hand, if desired, and the clock may 25 be dispensed with.

Having thus fully described my invention, what I claim as new, and desire to secure by Letters Patent, is—

1. A device of the kind described comprising 30 a hopper, a slide adapted to close the hopper at its lower end, means for automatically swinging the slide to either side of the hop-

per at a predetermined time, a second hopper below and partially inclosing the first-mentioned hopper, and a slideable sleeve carried by 35 the second-mentioned hopper adapted to regulate the rate of flow of grain.

2. A device of the kind described comprising a hopper having a flattened face adapted to fit a wall and having a vertical, semicylindrical groove formed in said face, a rod rotatably resting in the said groove and extending above and below the hopper, a slide carried 40 at the lower end of the rod and adapted to normally close the lower end of the hopper, 45 and means for rotating the rod at a predetermined time.

3. A device of the kind described comprising a hopper open at its lower end, a vertical rod rotatably arranged adjacent the hopper, 50 a slide carried by the lower end of the said rod and adapted to close the lower end of the hopper, the said rod being angled at its upper end, a chain connected to the upper angled portion of the rod, a pulley, the said chain 55 running over the pulley, a weight secured to the chain and adapted to draw the angled end of the rod to one side, and means for locking the weight against descent until a predetermined time.

VAN WYCK A. CROSHIER.
